United States Patent Office

Des. 203,606
Patented Feb. 1, 1966

203,606

VEHICLE FOR SNOW OR WATER

Leonard E. Greenberg, 195 Brewster Ave.,
West Hartford, Conn.

Filed Mar. 2, 1965, Ser. No. 84,050

Term of patent 14 years

(Cl. D34—15)

FIG. 1

FIG. 2

FIG. 3

FIG. 4

FIG. 5

FIG. 6

FIGURE 1 is a perspective view of a vehicle for snow or water embodying my new design;

FIGURE 2 is a top plan view thereof;

FIGURE 3 is a side elevational view thereof;

FIGURE 4 is a bottom view thereof;

FIGURE 5 is a front end elevational view thereof; and

FIGURE 6 is a rear end elevational view thereof.

I claim:

The ornamental design for a vehicle for snow or water, as shown.
